LOUIS SEXAUER, OF NEW YORK, N. Y.

Letters Patent No. 81,015, dated August 11, 1868.

IMPROVEMENT IN WATER-METERS.

The Schedule referred to in these Letters Patent and making part of the same.

TO ALL WHOM IT MAY CONCERN:

Be it known that I, LOUIS SEXAUER, of New York, in the county and State of New York, have invented a new and useful Improvement in Fluid-Meters; and I do hereby declare the following to be a full, clear, and exact description thereof, which will enable those skilled in the art to make and use the same, reference being had to the accompanying drawing, forming part of this specification, in which drawing—

Figure 1 represents a horizontal section of this invention taken in the plane indicated by the line xx , fig. 8, and looking in the direction of the arrow, opposite to that line.

Figure 2 is a transverse section thereof, the line yy , fig. 1, indicating the plane of section.

Figure 3 is a longitudinal section thereof, the plane of section being indicated by the line zz , fig. 1.

Figure 4 is a detached section of the valve, explaining the position thereof at a certain stage of the stroke. Similar letters indicate corresponding parts.

This invention relates to certain improvements on a fluid-meter, for which Letters Patent have been granted to Franz Wagner and myself, March 8, 1868.

These improvements consist principally in the arrangement of a diaphragm or piston, in combination with the levers and slide which impart motion to the valve, said diaphragm or piston being exposed to the direct action of the fluid, in such a manner that the valve is changed by the action of the fluid itself, and without the aid of springs.

The invention consists further in giving to the main piston a certain dead motion on its rod, in such a manner that during the interval occupied by this dead motion of the piston, the necessary time for changing the valve is obtained, and thereby the working parts of the meter are enabled to clear each other without binding.

A represents the piston of my meter, which is attached to a rod, B, and fitted into a cylinder, C.

The fluid to be measured enters the cylinder through the supply-pipe D, and it passes off through the discharge-pipe E, its course through the cylinder being changed by an oscillating-valve, F, which is so arranged that the fluid alternately passes in at one end and out at the other end of the cylinder, and that by the action of the fluid a reciprocating motion is imparted to the piston.

The valve is changed by two projections, a b , on the piston-rod, and by a series of levers, and a slide, as will be presently explained.

To the spindle of the valve is secured a lever, c , which is provided with a slot to catch over a stud, d , which projects from a slide, e .

This slide moves in suitable guides, f , attached to the inside of the valve-chamber, and it receives an intermittent reciprocating motion by a lever, g , which extends from the vertical rock-shaft h .

This rock-shaft has its bearing in a platform, i , secured to the inside of the valve-chamber, and to its lower end is secured a segmental disk, j , provided with two studs, k .

Between these studs moves a lever, l , which turns loosely on the rock-shaft h , and the end of which is connected by a pivot, m , with a lever, n , which connects by a pivot, o , with a lever, p .

This last-named lever is mounted on a rock-shaft, q , from which extends a lever, r , to the rod s of the diaphragm or supplementary piston t .

In the drawing, I have represented a diaphragm, which is secured in a chamber, G, under the valve-chamber, but it will be readily understood that this diaphragm can be replaced by a simple piston.

The chamber G communicates by a channel, u , (shown in dotted lines in fig. 2,) with the supply-pipe D, and by another channel, v , with the valve-chamber, so that the diaphragm is always exposed to the pressure of the fluid, which has a tendency to force the same back to the position which it occupies in figs. 1 and 3 of the drawing.

If the main piston, B, moves in the direction of the arrow marked near it in fig. 1, the projection a of the piston-rod strikes the fulcrum of the toggle-arms n l , and carries the same back beyond the line of equilibrium, during which part of the motion, the diaphragm t is carried out against the pressure of the fluid acting on it,

and the valve F is partially turned, but as soon as the fulcrum of toggle-arms *l* *n* has passed the line of equilibrium, the diaphragm *t* is carried back to its original position, by the pressure of the fluid, and the change in the position of the valve is completed. The motion of the piston is thereby reversed, the projection *b* strikes the toggle-arms *n l*, and the valve is again changed in the opposite direction, and so on.

When the piston approaches either end of its stroke, and the fulcrum of the toggle-arms comes close to the line of equilibrium, said toggle-arms being exposed to the pressure due to the action of the fluid on the diaphragm, have a tendency to pass the line of equilibrium, and to change the valve before the piston has completed its stroke. If this motion should take place, the correct operation of the meter would be disturbed, and I have therefore applied two stops, *a' b'*, to the upper surface of the piston-rod, and a projection, *c'*, to the slide *e*.

By these means, the slide is prevented from traversing across the piston-rod until the stops *a' b'* have cleared the projection *c'*.

When the piston has reached either end of its stroke, the valve is partly changed, (see fig. 4 of the drawing,) and the piston begins to return, while the change of the valve is completed by the pressure of the fluid on the diaphragm, and before the projection *c'* of the slide *e* has had time to clear the piston-rod. The piston *B* has therefore a dead motion on its rod, so that it will move a short distance without said rod, and thereby the ends of the stops *a' b'* are prevented from being forced against the projection *c'*, whereby the working parts of the mechanism would be strained, and unnecessary power would be consumed.

The motion of the piston-rod is confined by stops, *d'*, formed at either end, and coming in contact at one end of the stroke with the platform *i*, and at the other end with a projection, *e'*, secured to the said platform.

Having thus described my invention, what I claim as new, and desire to secure by Letters Patent, is—

1. The diaphragm or supplementary piston *t*, communicating with the supply-pipe *D*, and with the valve-chamber, in combination with the toggle-arms *n l*, piston-rod *B*, slide *e*, and valve *F*, substantially as and for the purpose described.
2. The stops *a' b'* on the piston-rod, in combination with the projection *c'* on the slide *e*, substantially as and for the purpose set forth.
3. Giving to the piston a dead motion on its rod, so as to gain time for the projection *c'* to clear the stops *a' b'*, as set forth.
4. The stops *d'* on the piston-rod, in combination with the projection *e'* and platform *i*, substantially as and for the purpose described.

LOUIS SEXAUER.
